UNITED STATES PATENT OFFICE.

HANS HONIGMANN, OF DULUTH, MINNESOTA.

AUTOMATIC FEEDING DEVICE FOR PRINTING-PRESSES.

1,074,720.

Specification of Letters Patent.

Patented Oct. 7, 1913.

Application filed December 26, 1911. Serial No. 867,761.

To all whom it may concern:

Be it known that I, HANS HONIGMANN, a citizen of the United States, residing at Duluth, in the county of St. Louis and State 5 of Minnesota, have invented certain new and useful Improvements in Automatic Feeding Devices for Printing-PresSES, of which the following is a specification, reference being had therein to the accompanying 10 drawing.

My invention relates to improvements in automatic feeding devices for printing presses, and pertains more particularly to the feeding of platen presses.

15 The object of my invention is to provide a feeder of this character which is self-contained and operated by the press operated mechanism and so arranged that it can be readily moved in or out of operative position 20 with the press and when moved out of position the press can be fed by hand in the usual manner.

Another object of my invention is to provide an automatic feeder in which the paper 25 is stacked therein and the sheets fed to the press and after being printed upon are removed and stacked without smearing or otherwise injuring the printed sheet.

A still further object of my invention is 30 to provide a feeder of this character so constructed and arranged that the swinging or moving thereof into operative position couples the working parts with a necessary working part of the press for operating the 35 feeder, and having certain details of structure hereinafter fully set forth.

In the accompanying drawings forming 40 part of this specification: Figure 1 is a side elevation of my improved reciprocating feeder, showing it in relative position in respect to the platen of the printing press. Fig. 2 is the opposite side elevation of the same. Fig. 3 is a top view of the same with stock-chute removed. Fig. 4 is a diagrammatic view of the reciprocating arm and feeder mechanism. Fig. 5 is an elevation partly broken away of the reciprocating arm quadrant operating mechanism. Fig. 6 is a fragmental section of the arm operating quadrant cam. Fig. 7 is a diagrammatic view of the arm elevating levers and cam. Fig. 8 is a perspective view of the hand or free end of one of the reciprocating feeder arms. Fig. 9 is a diagram of the 55 sheet feeding roller lifting mechanism.

1, represents the bull gear of an ordi-

nary platen printing press and 2 represents the platen of the press shown in position ready to receive a blank to be printed.

3, 4 and 5 represent the bottom, right side 60 and left side respectively of the frame which carries my improved feeder and which is preferably pivotally attached to the frame 6 of the printing press at 7, so that the entire feeder may be swung out of 65 engagement with the bull gear of the press at will, thus admitting of the use of the press for hand feeding with little inconvenience, however, the feeder may be attached in any other desired manner without 70 departing from the invention.

The spur gear 8 mounted upon the shaft 9 and within the frame of the feeder, meshes with the bull gear 1 and derives motion therefrom which is imparted to the main 75 gear 10 through the medium of the intermediate gear 11 also fixed upon the shaft 9 and revolved thereby. The main gear 10 is mounted upon and preferably intermittently connected to the main shaft 12 of the feeder 80 and imparts motion thereto, the shaft 12 being mounted transverse the uppermost portion of the feeder and journaled within and supported by the side walls 4 and 5 thereof.

85 A slidably reciprocal carriage is mounted within the side walls 4 and 5 of the frame and carries the two shafts 13 and 14, the former mounted within and carried by the sliding blocks 15 and 16, each of which are 90 formed with a tongue 17 which operates within a longitudinal groove 18 in the inner face of the side walls, and the latter carried within two short pivoted supports 19 and 20, they being pivotally mounted upon the 95 shaft 13 adjacent the ends thereof and carry within their free ends the shaft 14.

Rigidly attached to each of the blocks 15 and 16 and extending toward the front of the feeder therefrom are fixed the racks 21 and 22, which mesh with the gears 23 and 24. Intermediate the supports 19 and 20 and longitudinally adjustably mounted upon the shafts 13 and 14 are the supports 25 and 26 upon which are rigidly fixed the feeder arms 100 27 and 28 which reciprocate with the carriage as it goes to and fro.

An arm 29 is rigidly fixed to the support 105 20 and extends substantially parallel with the arm 27 and is for the purpose of raising and lowering the shaft 14, as the carriage goes back and forth and thus imparting a

vertical motion to the free ends of the arms 27 and 28 as they travel back and forth in order that they properly clear the upper edge of the platen in its travel and still deliver and remove the sheets at the proper time. A guide arm 30 is pivotally fixed to the short shaft 31 mounted within the side wall 5 and carries at its free end a guide roller 32 which engages the lower edge of the arm 29 and raises and lowers the same, the crank-arm 33 being also fixed to the shaft 31 and connected to the lower end of the vertically reciprocal bar 34 which straddles the shaft 12 and receives a reciprocal motion therefrom through the cam 35 being fixed to the shaft 12 and engaging the roller 36 mounted within the upper extremity of the bar 34, this cam being so adjusted as to properly time the raising and lowering of the feeder arms, the shaft 14 rocking up and down with the arm 29 and thus imparting the identical motion to the feeder arms. The racks 21 and 22 are operated longitudinally by means of the small gear wheels 23 and 24, as before stated, they being mounted upon the shaft 37 which extends entirely across the feeder frame, said shaft 37 deriving its power through the gear 38 keyed to the counter shaft 39, which is operated by the gear 40 also fixed to the same shaft and meshing with and being driven by the geared quadrant 41 which is pivotally mounted upon the shaft 12 and having an upwardly projecting crank arm 42 connected with the arm 43 adjustably mounted within the rocker arm 44 pivotally carried by the stub shaft 45.

The arm 44 is rocked back and forth by means of the cam arm or pitman 46, one end of which is connected to said arm intermediate the connection of the arm 43 and the shaft 45, and the upper end carries the roller 47 which travels within the race cam channel 48 in the cam wheel 49. The cam channel 48 in the wheel 49 is such that the feeder arms are held stationary when the sheet of paper on the platen is being printed upon.

The pitman 46 is formed with the slotted opening 50 therein which straddles the shaft 12 and maintains the proper vertical position of the pitman as clearly shown in Fig. 5 of the drawings. Thus when the cam wheel 49 revolves, which it does in an anti-clockwise direction at all times, the cam channel will impart a reciprocating motion to the pitman 46, which will, through the connection above described oscillate the quadrant 41 and impart motion to the train of gears with which it meshes, first in one direction and then in the opposite as clearly seen, which results in the racks 21 and 22 with the carriage and feeder arms above described being drawn forward to their pre-

determined position and then returned, at every revolution of the shaft 12.

A preferred auxiliary sheet feeding mechanism for feeding the sheets at intervals to the feeder arms 27 and 28 comprises the large shaft 51 extending parallel with the main shaft 12 and carrying two flexible rollers 52 which engage the foremost individual sheet of the stack 53 in the stock chute 53' at the time when said rollers are depressed to engage the same.

The shaft 51 receives an oscillating motion through the train of gears 54, 55, 56, 57 and 58, 54 being fixed to the shaft 51, 55 being mounted upon a rockable stub shaft 59, 56 being loosely mounted upon the shaft 37 and 57 and 58 fixed to the counter shaft 60, which latter is driven by the gear 58 engaging the quadrant 61 pivotally mounted upon the stub shaft 31. The quadrant 61 is raised and lowered by means of the adjustably connected pitman 62 connected to the crank arm 63 fixed to the extreme end of the shaft 12 and thus oscillating motion is transmitted to the shaft 51.

The rolls 52 upon the shaft 51 are prevented from engaging the blanks to be fed to the feeder arms except at such times when the shaft is revolving properly and the rhythm of the press is in order, by the mounting of the shafts 51 and 59 within the rockable frame 64 pivotally mounted upon the shaft 37, the shaft 59 being simply a stiffening rod uniting the two sides 64 and keeping the shaft 51 in line, the intermediate gear 55 being loosely carried by the shaft 59. One of the frame members 64 as shown in Fig. 9 is formed with a projecting lug 65, which engages and rests upon the toe 66 of the cam operated vertically reciprocal pitman 67 which straddles the shaft 12 and derives motion therefrom through the cam 68 being fixed to the shaft and engaging the roller 69 mounted within the upper extremity of the pitman 67. Thus the rolls 52 are kept from engaging with the stock stack 53 until such predetermined time as necessary to be in step with the machine, as determined by the adjustment of the cam 68 in order to properly deliver the sheet to the reciprocating feeder arms when the latter are ready to receive it.

I do not wish to confine this invention to the above described specific form of auxiliary feeder for delivering the blanks to the feeder arms as it is evident that the same may be accomplished in many other ways.

The outer free ends of the reciprocating feeder arms 27 and 28 are each provided with an automatically operated mechanism for positively engaging and holding each blank *en route* to the press and releasing it at the proper moment, also means for carrying off the printed sheet. In Fig. 8 such means are clearly shown and are de-

scribed as follows: 70 represents the extreme end of one of the arms which is formed with a notch or hook 70' in the lower extreme face thereof which hooks over and engages the lower edge of the printed sheet and draws the same off the platen when the arms return and delivers it to the continuously revolving endless belt or belts 71 mounted upon the rollers 72 and 73, which carry it to the printed pile 74 which is common in automatic printing press feeders. A laterally projecting arm 75 is attached to the main feeder arm near the extreme end 70 thereof, the outer end extending substantially parallel therewith and supporting considerably above the extreme end 70 a transverse frame 76, which has loosely mounted within it the small shaft 77 carrying upon its innermost end the gripping dog 78 and upon its outermost opposite end the trip lever 79. The trip lever 79 has a toggle connection 80 to the pivoted lever 81 which is attached to the arm 75 at 82, thus when the trip lever is depressed, the lower extremity of the toggle connection will extend considerably below a plane with the bottom of the feeder arms as shown in Figs. 1 and 2, so that at the moment the fingers are dropped upon the platen, this toggle connection will impinge the same and be forced upward into the position shown in Fig. 8, thus revolving the shaft 77 and operating the gripping dog 78. Now the gripping dog is in the form of a hook having an upwardly extending arm 83 formed integral therewith and when the dog is in its lowermost position, the hooked portion passes down adjacent the outer edge of the feeder finger or arm while the arm 83 rests thereupon, pinching and holding fast any blank or sheet between itself and the upper surface of the feeder arm that has been previously placed there.

At the time the blank is fed to the hands of the feeder arms, the dog 78 is in a partly depressed position and the hook thereof is somewhat below the upper edge of the arm and in the act of being depressed, so that the blank cannot pass thereby and a further descent of the dog will bring the arm 83 in contact with the blank and hold it. The descent of the dog and toggle above described is caused by the suspended rod 84 in the arms 85 and 86 mounted upon the cross shaft 87 and deriving oscillatory motion from the rearwardly extending portion 88 of the arm 86 being actuated by the cam 89 upon the shaft 12 engaging the same. A spiral spring 87' upon the shaft 87 being so adjusted as to keep the arms 85 and 86 in their uppermost position normally.

The cam 89 is so positioned as to properly time the descent of the rod 84 in order to engage the trip 79 and cause the dog to grip the incoming blank upon the hands of the

feeder arms at the proper moment. The hooked or curved portion of the dog 78 also acts as a retarder to the sheet in leaving the hands of the feeder arms and prevents such delivery being too sudden. A short arm 90 is rigidly fixed to the shaft 77 and carries the small roller 91 which engages the leaf spring 92, the latter being fixed to the arms 75 and arched in such a manner as to normally hold the roller securely in either of its extreme positions, thus insuring positive action of the gripping mechanism.

The sheets to be printed are piled in the stock chute 53' in the manner shown in Fig. 4 of the drawings. The bull gear 1 of the platen press is driven by the press and this starting of the press starts the feeder to operate. The bull gear meshes with the gear 8, which carries a smaller gear 11, which meshes with the main gear 10. The said main gear is mounted upon the shaft 12, and is intermittently connected to said shaft for intermittently driving the same and through the medium of the train of gearing the flexible roller 52 engages a sheet of paper from the stack in the chute 53', and delivers it to the feeder arms 27 and 28. The shaft 12, after this operation, is stopped and thus another sheet of paper is not immediately fed to the arms. The paper as it is fed to the arms is gripped by the mechanism at the outer end. The arms by means of the racks 21 are moved outwardly and carry with them the sheet of paper and it is properly positioned on the platen 2. The operation is repeated, feeding another sheet of the platen, and upon the return of the feeder arms 27 and 28 on this second operation, the hook 70' engages the previously printed sheet and draws it rearwardly when dropped upon the endless conveyer 71, and it is conveyed to the stock pile 74 of printed sheets.

Having thus described my invention, what I claim and desire to secure by Letters Patent is—

1. The combination with a platen printing press, of a frame pivoted adjacent thereto adapted to be swung into or out of operative position with respect to said press, a carriage reciprocating within said frame, radially movable feeder arms carried by the carriage for carrying sheets of paper to and from the platen of the printing press, and means for operating said carriage and adapted to interlock with a necessary operative part of the press when the frame is swung around into operative position.

2. The combination of a platen printing press, of a frame pivoted adjacent thereto adapted to be swung into or out of operative position with respect to said press, a reciprocating carriage within the frame, radially movable reciprocating arms carried by the carriage for conveying sheets of paper

- to and from the platen printing press, and means operated by the press for operating said arms when the frame is swung into operative position.
5. The combination with a platen printing press, of a frame pivoted adjacent thereto, a carriage reciprocating in said frame, radially movable reciprocating feeder arms carried by the carriage for conveying sheets of paper to and from the platen of the press, means carried by the free ends of the arms for gripping and holding the sheets while feeding them to the platen of the press, and means operated by the press for operating the reciprocating feeder arms.
10. The combination with a platen printing press, of a frame pivoted adjacent thereto adapted to be swung into or out of operative position with respect to said press, radially movable reciprocating feeder arms carried by the frame for conveying sheets of paper to and from the platen of the press, and a gearing carried by the frame for operating the feeder arms and adapted to interlock with the driving gear of the press when the frame is swung around into operating position.
15. The combination with a platen printing press, of a frame pivoted adjacent thereto adapted to be swung into or out of operative position with respect to said press, radially movable reciprocating feeder arms carried by the frame for conveying sheets of paper to and from the platen of the press, automatic means at the free end of the feeder arms for gripping and holding the sheets while they are fed to the platen of the press, means for reciprocating the feeder arms and adapted to interlock with an operative part of the press when the frame is swung into operative position.
20. The combination with a platen printing press, of a frame pivoted adjacent thereto adapted to be swung into or out of operative position with respect to said press, a carriage reciprocating within said frame, radially movable feeder arms carried by the carriage for conveying the sheets of paper to and from the platen of the press, automatic means at the free end of the feeder arms for gripping the sheets while being fed to the press, means for reciprocating the carriage, said reciprocating means adapted to be coupled with an operative part of the press when the frame is swung around into operative position.
25. The combination with a platen printing press, of a frame pivoted adjacent thereto adapted to be swung into or out of operative position with respect to said press, a carriage reciprocating within said frame, radially movable feeder arms carried by the carriage for conveying the sheets of paper to and from the platen of the press, means for reciprocating the carriage, said reciprocating means adapted to be coupled with an operative part of the press when the frame is swung around into operative position.
30. The combination with a platen printing press, of a frame pivoted adjacent thereto adapted to be swung into or out of operative position with respect to said press, a carriage reciprocating within said frame, radially movable feeder arms carried by the carriage for conveying the sheets of paper to and from the platen of the press, means for reciprocating the carriage, said reciprocating means adapted to be coupled with an operative part of the press when the frame is swung around into operative position.
35. The combination with a platen printing press, of a frame pivoted adjacent thereto adapted to be swung into or out of operative position with respect to said press, a carriage reciprocating within said frame, radially movable feeder arms carried by the carriage for conveying the sheets of paper to and from the platen of the press, means for reciprocating the carriage, said reciprocating means adapted to be coupled with an operative part of the press when the frame is swung around into operative position.
40. The combination with a platen printing press, of a frame pivoted adjacent thereto adapted to be swung into or out of operative position with respect to said press, a carriage reciprocating within the frame, radially movable feeder arms carried by the carriage for conveying the sheets of paper to and from the platen of the press, rack bars carried by the carriage, gears meshing with the rack bars for reciprocating the carriage and means carried by the frame for rotating the gears and adapted to be driven by the press when the frame is swung around into operative position.
45. The combination with a platen printing press, of a frame pivoted adjacent thereto adapted to be swung into or out of operative position with respect to said press, a carriage reciprocating within the frame, radially movable feeder arms carried by the carriage for conveying the sheets of paper to and from the platen of the press, rack bars carried by the carriage, gears meshing with the rack bars for reciprocating the carriage and means carried by the frame for rotating the gears and adapted to be driven by the press when the frame is swung around into operative position.
50. The combination with a platen printing press, of a frame pivoted adjacent thereto adapted to be swung into or out of operative position with respect to said press, a carriage reciprocating within the frame, radially movable feeder arms carried by the carriage for conveying the sheets of paper to and from the platen of the press, rack bars carried by the carriage, gears meshing with the rack bars for reciprocating the carriage and means carried by the frame for rotating the gears and adapted to be driven by the press when the frame is swung around into operative position.
55. The combination with a platen printing press, of a frame pivoted adjacent thereto adapted to be swung into or out of operative position with respect to said press, a carriage reciprocating within the frame, radially movable feeder arms carried by the carriage for conveying the sheets of paper to and from the platen of the press, means at the free end of the feeder arm for gripping and holding the sheets while being fed to the platen of the press, and a bell crank lever operated by the gearing and adapted to raise and lower the said arms.
60. The combination with a platen printing press, of a frame pivoted adjacent thereto, a carriage reciprocating within the frame, radially movable feeder arms carried by the carriage for conveying sheets of paper to and from the platen of the press, means at the free end of the feeder arm for gripping and holding the sheets while being fed to the platen of the press, and a bell crank lever operated by the gearing and adapted to raise and lower the said arms.
65. The combination with a platen printing press, of a frame pivoted adjacent thereto, a carriage reciprocating within the frame, radially movable feeder arms carried by the carriage for conveying sheets of paper to and from the platen of the press, means at the free end of the feeder arm for gripping and holding the sheets while being fed to the platen of the press, and a bell crank lever operated by the gearing and adapted to raise and lower the said arms.

per to and from the platen of the printing press, rack bars carried by the carriage a gearing meshing with the rack bars for reciprocating the carriage, means operated by the platen operating means for engaging the sheets of paper and delivering them to the feeder arms and adapted to raise and lower the said arms.

13. The combination with a platen printing press, of a frame pivoted adjacent thereto, radially movable reciprocating feeder arms carried by the frame for conveying sheets of paper to and from the platen of the press, automatic means at the free end of the feeder arm for gripping and holding the sheets as they are fed to the press, means carried by the frame for reciprocating the arms and means operated by the arms reciprocating means for radially moving the feeder arms, substantially as shown and described.

14. The combination with a platen printing press, of a frame pivoted adjacent thereto, a carriage reciprocating within the frame, radially movable feeder arms carried by the carriage for conveying the sheets of paper to and from the platen of the press, automatic means at the free end of the arms for gripping and holding the sheets as they are fed to the platen of the press, a gearing for reciprocating the carriage, means for reversing the gearing and thereby reversing the reciprocating movement of the carriage, and means operated by the gearing for radially moving the feeder arms.

15. The combination of a platen printing press, of a frame pivoted adjacent thereto, a reciprocating carriage in the frame, radially movable feeder arms carried by the carriage, for conveying the sheets to and from the platen of the press, automatic gripping means at the free end of the feeder arms for gripping and holding the sheets as they are fed to the platen of the press, rack bars carried by the carriage, a gearing meshing with the racks for reciprocating the carriage, means operated by the platen operating means and engaging the lower face of the feeder arms for raising and lowering the said arms at the proper time and means for reversing the gearing, whereby the carriage and the feeder arms are reciprocated back and forth.

16. The combination with a platen printing press, of a frame pivoted adjacent thereto, a carriage reciprocating within the frame, radially movable feeder arms carried by the carriage for conveying sheets of paper to and from the platen of the press, rack bars carried by the carriage, a gearing meshing with the rack bars for reciprocating the carriage, means for reversing said gearing, means operated by the platen operating means for moving the arms radially, whereby the arms are raised and

lowered at the proper time to cause the accurate feeding of the sheets to and from the platen of the press.

17. The combination of a platen printing press, of a frame adjacent thereto, a carriage reciprocating within the frame, radially movable feeder arms carried by the carriage for conveying the sheets of paper to and from the platen of the press, automatic mean at the free ends of the feeder arms for gripping and holding the sheets as they are fed to the platen of the press, rack bars carried by the carriage and gearing engaging the rack bars, for reciprocating the carriage, a reversing mechanism operated by the platen operating means for raising and lowering the feeder arms at the proper time, whereby the sheets are fed to the platen of the press.

18. The combination with a platen printing press, of a frame adjacent thereto, a carriage carried by the frame, radially movable feeder arms carried by the carriage, for conveying the sheets of paper to and from the platen of the printing press, automatic means at the free end of the feeder arms for gripping and holding the sheets as they are fed to the platen of the press, means for reciprocating the carriage and means for raising and lowering the feeder arms for causing the same to feed the sheets of paper to and from the platen of the press.

19. The combination with a platen printing press, of a frame adjacent thereto, a carriage reciprocating within the frame, radially movable feeder arms carried by the carriage for carrying the sheets of paper to and from the platen of the press, gripping means carried by the outer ends of the arms, means for reciprocating the carriage and holding it at a standstill while the sheet is being printed upon, and a cam mechanism operated by the carriage operating mechanism for raising and lowering the feeder arms in unison with the reciprocation of the carriage.

20. The combination with a platen printing press, of a frame adjacent thereto, a carriage reciprocating within the frame radially movable feeder arms carried by the carriage for conveying the sheets of paper to and from the platen of the press, means operated by the press for reciprocating the carriage, means for allowing the carriage to remain still while the sheet is being printed upon, a cam operated by the carriage operating mechanism for raising and lowering the feeder arms in unison with the reciprocation of the carriage, and a segment member for operating and feeding the sheets of paper from the hopper to the feeder arms.

21. The combination with a platen printing press, of a frame pivoted adjacent thereto and adapted to be swung into or out of operative position in respect to said press, a

carriage within said frame, radially movable feeder arms carried by the carriage for conveying sheets of paper to and from the platen of the printing press, and means for operating the said carriage and adapted to be interlocked with the necessary operative part of the press when the frame is swung around into operative position.

22. The combination with a platen printing press, of a frame pivoted adjacent thereto and adapted to be swung into or out of operative position with respect to said press, a reciprocating carriage within the frame, arms carried by the carriage for conveying sheets of paper to and from the platen of the printing press, and means operated by the press for operating the arms when the frame is swung into operative position.

23. The combination with a platen printing press, of a frame pivoted adjacent thereto, a carriage in said frame, reciprocating feeder arms carried by the carriage for conveying sheets of paper to and from the platen of the press, means carried by the free ends of the arms for gripping and holding the sheets while feeding them to the platen of the press, and means operated by the press for operating the reciprocating feeder arms.

In testimony whereof I hereunto affix my signature in the presence of two witnesses.

HANS HONIGMANN.
